UNITED STATES PATENT OFFICE

2,651,283

CONVEYER AND ADHESIVE APPLICATOR
FOR CARTON BLANKS

Julius A. Zinn, Jr., Chicago, Ill.

Application June 30, 1949, Serial No. 102,345

3 Claims. (Cl. 118—2)

1

This invention relates to a new and improved conveyor and adhesive applicator and more particularly to a conveyor for taking blanks from a stack and conveying them singly to a gluer which applies an adhesive to selected areas on the blanks and then delivering the blanks to a machine for forming them into boxes or cartons.

The apparatus is especially designed to handle blanks of irregular outline and shape such, for example, as are cut to form tapered cartons or such as are provided with tabs or lugs for interlocking to provide leakproof corners. Such blanks, when delivered, to carton forming machines such as that shown in my application Serial No. 752,364, filed June 4, 1947, now Patent 2,547,899, must be delivered with a predetermined edge toward the machine. Due to the irregular edges of the blank, it is impractical to mechanically separate one blank from the bottom of a pile of similar blanks by movement of the blank in the direction required for final delivery to the machine because the blanks tend to become interlocked. The conveyor of the present invention, therefore, provides for separating a blank from the stack by initial movement of the blank in one direction followed by a change in direction of the blank upon a following section of the conveyor.

The production of cartons or boxes which are liquid tight requires very accurate delivery of the blanks and very accurate application of the glue or adhesive to predetermined areas of the blank. It is important that the selected areas be completely covered with the adhesive and is also quite important that adhesive be not applied to non-selected areas.

It is also important that the blanks be delivered in a clean condition. Many such blanks are used for packaging food and cleanliness is important as well as the appearance of the product. The conveyor system has, therefore, been designed so that the blanks cannot become contaminated or soiled by lubricating material or other foreign matter.

It is an object of the present invention to provide a new and improved conveyor and apparatus for applying adhesive.

It is a further object to provide apparatus which provides for separation of irregular blanks by movement in one direction followed by delivery from the conveyor in another direction, presenting a different side of the blank toward the point of delivery.

It is also an object to provide apparatus for accurately delivering blanks to means for ap-

2

plying adhesive to selected portions of their surfaces.

It is another object to provide a conveyor for positively passing blanks against a rotating adhesive applying drum independently of frictional drive by contact with the drum.

It is an additional object to provide adhesive applying apparatus having means for adjusting the quantity of adhesive applied to the blanks and for controlling pressure of the blank against the adhesive applying means.

It is a further object to provide means for automatically stopping feed of adhesive to the adhesive applying means when the conveyor is in operation but is not feeding blanks to the adhesive applying means.

It is also an object to provide apparatus of this character which is efficient in operation and adapted for commercial production and use.

Other and further objects will appear as the description proceeds.

I have shown certain preferred embodiments of my invention in the accompanying drawings, in which—

Figure 1 is a plan view of the apparatus, partly broken away;

Figure 2 is an elevation of the adhesive applying apparatus on an enlarged scale;

Figure 3 is a section taken on line 3—3 of Figure 1;

Figure 4 is a section taken on line 4—4 of Figure 1;

Figure 5 is a section taken on line 5—5 of Figure 1;

Figure 6 is a section taken on line 6—6 of Figure 1;

Figure 7 is a section taken on line 7—7 of Figure 1; and

Figure 8 is a longitudinal fragmentary section, on an enlarged scale, of the adhesive applying apparatus and the associated section of the conveyor.

Referring first to Figure 1, it will be seen that the conveyor and adhesive applying apparatus are supported on an L-shaped framework having the longer portion 21 and the shorter portion 22. This portion 22 carries the mechanism for supporting and feeding a stack of blanks, as shown in vertical longitudinal section in Figure 4 and vertical cross-section in Figure 3. The long portion 21 of the supporting frame carries a series of conveyors and the adhesive applying apparatus. It feeds the blanks to the rotating table 22 of the carton forming apparatus.

Considering first the feed apparatus and refer-

ring to Figures 1, 3 and 4, a pair of vertically extending adjustable guides are shown at 23, these engaging rear portions of the stack of blanks 24. At either side of these guides 23 are located the pair of guide and support rollers 25 which engage the outer edge portions of the rear of the blanks. As clearly shown in Figure 1, all of these guides are adjustable in the cross frame member 26 laterally and are slotted for adjustment toward or away from the stack of blanks so as to be used with various types and shapes of blanks. The particular blanks for which the guides are adjusted have portions extending rearwardly, or to the right in Figure 4, of the guides 23 and resting on rollers 25. The lateral edges of the blanks are guided between the stack guides 23 shown in Figures 3 and 4. The front edges of the blanks engage the vertical stop members 29. The vertical adjustable holding members 31 limit movement to one blank at a time.

The lower blank is withdrawn from the stack located and held by these guides by means of contact elements 30 carried by the wheels 32 and 33, these contact or friction elements being preferably formed of a type of rubber or other material adapted to frictionally pick up the blank. The remaining portions of the periphery of wheels 32 and 33 are formed of smooth material which will slide over the blank without frictional engagement sufficient to remove the blank. The wheels 32 and 33 are carried by pulley shaft 34 and between the wheels 32 and 33 are located pulleys 35 over which extend feeder belts 37. The pulleys 35 have recessed faces with edges 38 extending above the belts 37 so that the belts do not engage the lowermost blank in the stack until it has been moved forward by the contact elements 30. These belts 37 extend to the left, as shown in Figure 4, around idler pulleys 39 which may be adjusted to tension the feeder belts. The shaft 34 is driven from power shaft 40 and the pulley 42 thereon by means of the belt 43 which passes over idler pulley 44 and around pulley 46, as seen at the left of Figure 3.

The blanks are held down against the belts 37 by the rollers 47 held in frames 48 and pressed downwardly by compression springs 49 which are carried by the roller adjusting studs 50. These studs 50 extend from supporting arms 52 which extend around above and are secured to the upper face of the cross frame member 54. The arms 52 are capable of lateral adjustment on member 54. The upper feed rollers 56 located adjacent the front of the stack guides are adjustably carried by means of slotted arms 57 from the brackets 52. Below the belts 37 and opposite a portion of the upper guide roller assembly, including rollers 47, are located support rollers 60. These are carried by brackets 61 supported from the cross frame members 62 and 63, which members also, by means of brackets 65, adjustably support idler rollers 39. These rollers 39 may be adjusted to take up slack in belts 37.

The small transfer roller 67 is located beyond the end of the upper run of the conveyor belts 37 and at right angles to the line of movement of the blanks. This roller 67 is driven by belt 69 from pulley 70 which is also carried by the shaft 40. The transfer roller 67 carries the blank over against the flaring guide 74 and holds them in contact therewith until upon lateral movement their rear or right edges, as seen in Figure 4, reach the guide member 100 and fit into groove 101 therein. An electric switch 75 located above guide 74 is actuated by a blank should it fail 75

to enter the guide 74. At this time the left edge of the blank will have passed into groove 98 in the left guide 97. The guide 74 locates the blanks under the overhead conveyor 80, which conveyor comprises chains running around pairs of pulleys 82 and 84 carried by shafts 86 and 88. As shown in Figures 5 and 6, the cross shaft 88 is provided with a gear 90 which meshes with a gear 91 carried on a lower cross shaft 92. The drip pan 94 is carried adjacent the lower runs of the chains 80 and above the moving blanks. The chains 80 carry the pick-up members 96 which extends laterally of the pan 94 and below the level of that pan when they are on the lower run of the chains.

From the flaring guide 74 extends the close fitting guide member 97 having the slot 98 formed therein. On the opposite or right side of the conveyor assembly, as seen in Figure 6, is located a guide 100 similar to the guide 97, this having a slot 101 similar to the guide slot 98. Therefore, at this point in their travel, the blanks are closely guided as to their line of movement.

As seen in Figures 5, 6 and 8, the overhead conveyor chains 80 terminate above the beginning of the run of lower conveyor chains 110. These chains pass over drive sprockets 111 on shaft 92, over idler sprockets 112 on shaft 114, around under idler sprockets 116 on shaft 117 and 118 on shaft 119. This lower conveyor, as best shown in Figures 6 and 7, operates by means of the main flight cross members 121 which extend between the two chains 110 below the cover plates 123 and 124 which carry the guide members 97 and 100. These plates 123 and 124 also carry the rails 126 and 127 over which the blanks slide. The cross members 121 carry the adjustable pusher members or tabs 130 which, as shown in Figure 6, take up their thrust against the rear edge of the blanks as they are left by the downwardly extending arms 96 of the previous overhead conveyor. These members 130 are secured to cross members 121 by bolts 131 and may be given any desired angular adjustment to fully contact a rear edge of the blanks.

The chains 110 pass between the lower pressure roll 135 and the upper adhesive applying roll 136. It will be understood that adhesive is only applied to selected areas of the blank and the roll 136 has raised portions 137 for this purpose. Roll 135 is keyed to shaft 138 and roll 136 is keyed to shaft 139. These shafts 138 and 139 are driven in synchronism with each other and with the drive of the conveyor belts 110. The pressure roller 135 is provided with a recess 141 which extends parallel to the axis of the roller and is adequate in size to receive and permit passage of the cross members 121 and pusher tabs 130 carried by the conveyor chains 110. Consequently, the blank is carried through between the pressure roll 135 and the adhesive roll 136 positively by the conveyor and independent of any frictional gripping by the two rollers. Small spaced wires 146 are carried on rods 148 extending from the side frames, these wires serving to strip the blanks from the adhesive applying surfaces 137. The surfaces 137 may be provided with narrow grooves to receive the wires. An electric switch 151 is located adjacent the discharge beyond wires 146 and is operated by the blanks if they should jam at this point.

As shown in Figure 2, the shaft 138 of the pressure roller 135 is carried in sliding bearing blocks 140 guided in the frame 144. Each block 140 is provided with an adjustable stud 147 which rests on an eccentric 149 keyed to shaft 150.

This shaft 150 is rotated by knob 153 on pointer 157. The spacing between the roller 135 and the adhesive applying roller 137 may thus be adjusted for blanks of different thickness or to apply different degrees of pressure at this point.

The underneath conveyor just described delivers the blanks after the application of glue to a second overhead conveyor comprising chains 142 passing, at the left end of the run, over sprockets 143 carried by cross shaft 145. As shown in Figure 5, these chains 142 pass, at the right end of their run, over sprockets 147 which are located on a shaft carried by the blocks 149 which may be adjusted by screws 150 and nuts 152 carried by the right end of the frame 154 which supports this second overhead conveyor. These chains 142 are provided with the spaced carriers 155 similar to the members 96 of the first overhead conveyor. This conveyor is also provided with the oil pan 156 under the lower run of chains 142.

The gluer, as best shown in Figure 8, comprises the pan 160 above which is supported the transfer roll 161 rotating with shaft 162 to which it is keyed. This roller 161 dips down into pan 160 below the level of the adhesive therein. It rotates in the clockwise direction and the thickness of the adhesive carried by the transfer roll for transfer to the raised adhesive depositing surfaces on roller 137 is determined by the doctor roll 163 located adjacent and to the left of transfer roll 161, as shown in Figure 8.

A source of light 170 is located below the upper run of conveyor chains 110, as seen in Figure 8, and an electric eye 172 is also located below this run. Above the run is located a flat tubular member 174 carrying downwardly facing inclined mirrors at either end thereof, these mirrors being located above the source of light 170 and the electric eye 172, respectively. It will be apparent, therefore, that if either the gap between the electric eye and its mirror or that between the source of light and its mirror is blocked by passage of a blank, the electronic eye will not be operated since no light will pass to it. In normal operation the blanks are so spaced that one or the other portions of the light path is always blocked. Consequently, the control device actuated by the electric eye does not function. If, however, no blanks are being fed through this electric eye control, it serves to actuate a solenoid 175 shown in Figure 2 which, by pulling down on link 176, through arm 177, link 178, and lever arm 180, rotates eccentric supports 182 for the ends of the shaft supporting doctor roll 163 so as to move that roll into close contact with the transfer roll 161 so that no adhesive is transferred to the raised portions of the adhesive applying roll 137. The scraper 165 removes adhesive from the doctor roll 163, which rotates in the counter-clockwise direction, so that adhesive pick up by the doctor roll 163 is not returned to the transfer roll 161.

In the operation of the conveyor to feed blanks to the carton making machine, a stack of blanks 24 are placed in position between the various guides, as shown in Figure 4. Portions of the rear edges of the blanks engage the face of the vertical guides 23, while the lowermost blank has portions of its rear edges resting on the guide rollers 25. With power supplied to all of the conveyors, the raised pulley edges 38 and the wheels 32 and 33 slide under the lower forward edges of the bottom blank until the contact elements 30 on the wheel surfaces engage the blank. These contact elements draw the blank out and

its front edge passes below the lower edge of members 31, under the rollers 56 and on top of the belts 37. The belts 37 carry them under the series of rollers 47, the pressure of these 5 rollers holding them frictionally against the belts. The belts feed them out until they are delivered over the transfer roller 67 which is positively driven. This roller 67 continues to move the blank forward until its forward edge rests against the lower portion of the flaring guide member 74. The parts are so timed that immediately after a blank reaches this position, the chains 80 of the overhead conveyor bring pick-up or carrier members 96 against the left edge of the blank, as considered in relation to Figures 1 and 5. These members 96 carry the blanks to the right until their edges are fitted in the slot 98 in member 97 and into slot 101 in guide 100. By these means, the blank is very accurately located in its movement.

As the blank passes from the right end of this first overhead conveyor, it is picked up by an adjustable pusher or pick-up member 130 carried by a cross member 121 of the lower conveyor. This member 130 has been adjusted to the angle of the adjacent edge of the blank so that it has a full contact therewith and has no tendency to jam the edges of the blank in the guide grooves.

The blank is carried by the lower conveyor over and between the adhesive applying roll 136 and the pressure roll 135. As clearly shown in Figures 5 and 8, the cross member 121 and pusher member 130 pass through between the two rolls, thus assuring exact registration of the blank with the raised adhesive applying portions 131 of the surface of cylinder 136. As the blank leaves the right end of this conveyor, it is picked up by the carriers 155 of the second overhead conveyor. This conveyor delivers the blanks at its end to the point of use, such as the rotating table 22, a portion of which is shown in Figure 1, of the carton forming machine fully shown in my co-pending application which has been identified above.

All of the conveyors have their drives and the locations of their pusher members coordinated so that the movement of the blank through the conveyor system may be exactly coordinated with the movement of the receiving apparatus. The removal of the lowermost blank of the pile by movement in one direction followed by movement of the blank at right angles through the gluer to the delivery point is an important feature of the invention. This makes possible automatic operation and delivery of single blanks from types of blanks which cannot be separated by mechanical movement when initially moved laterally in the manner in which they are required to be delivered. This is caused by the configuration of the blanks with tabs extending therefrom with narrow spaces therebetween. Such blanks can be mechanically separated in line with the tabs and divisions, but not at right angles thereto. Any slight flexing of the blanks which will normally occur in handling them will cause interlocks of the edges of the tabs which would jam any apparatus attempting to separate them laterally. The fact that the blanks are positively carried by a conveyor through and in contact with the adhesive applying roll is important, as only in this way can slippage be prevented and accurate registration made of the glue applying raised portions of the roller against the blanks.

The conveyor and gluing apparatus is supplied with power through shaft 164 and universal joint 166 to the electric clutch 167. This clutch may be of any standard construction and its details form no part of the present invention. It is provided with a plurality of power and control leads 168. Manually operable control switches 185, 186 and 187 are provided at convenient points, as shown in Figure 1. The automatically operating switches 151 and 15 are also connected in the control circuit and serve to release the clutch should blanks jam at their locations. The switches 185, 186 and 187 may be used to release the clutch or to put it in operation by manual control.

It will be understood that since the conveyor is driven from the machine operating upon the blanks, the clutch 167 serves to stop the conveyor without stopping operation of the machine or other apparatus, such for example as means for applying wax to the formed cartons, which may be synchronized with the machine.

While I have shown certain preferred embodiments of my apparatus, these are to be understood to be illustrative only as it is capable of change and variation to meet differing conditions and requirements, and I contemplate such modifications as come within the spirit and scope of the appended claims.

I claim:

1: A conveyor and gluer assembly comprising a supporting frame, guides for guiding linear movement of flat blanks on the frame, an adhesive applying roll above the guides, a pressure roll below the guides, a conveyor adapted to move blanks through and between said rolls, an adhesive feeding roll adjacent the adhesive applying roll, and means adjacent the conveyor operative when the conveyor is clear of blanks to remove adhesive from the feeding roll prior to contact with the applying roll, said means comprising a doctor roll, a light source and electric eye below the guides, reflecting means above the guides, and solenoid operated means controlled by the electric eye, said solenoid operated means operating the doctor roll to remove adhesive from the applying roll.

2: A conveyor and gluer assembly comprising a supporting frame, guides for guiding linear movement of flat blanks on the frame, an adhesive applying roll above the guides, an pressure

roll below the guides, a conveyor adapted to move blanks through and between said rolls, an adhesive feeding roll adjacent the adhesive applying roll, an adhesive sump into which the lower portion of the feeding roll extends, adjustable control means adjacent the feeding roll for controlling the thickness of the layer of adhesive carried by said roll, and means adjacent the conveyor operative when the conveyor is clear of blanks to actuate said adjustable control to remove adhesive from the feed roll before contact with the applying roll.

3. A conveyor and gluer assembly comprising a supporting frame, guides for guiding linear movement of flat blanks on the frame, an adhesive applying roll above the guides, a pressure roll below the guides, a conveyor adapted to move blanks through and between said rolls, an adhesive feeding roll adjacent the adhesive applying roll, an adhesive sump into which the lower portion of the feeding roll extends, adjustable control means adjacent the feeding roll for controlling the thickness of the layer of adhesive carried by said roll and means adjacent the conveyor operative when the conveyor is clear of blanks to actuate said adjustable control to remove adhesive from the feed roll before contact with the applying roll, said means comprising a light source and electric eye below the guides, reflecting means above the guides and solenoid operated means controlled by the electric eye for actuating the adjustable control.
